UNITED STATES PATENT OFFICE.

EBEN H. MACKINLAY, OF CALGARY, ALBERTA, CANADA.

DOOR-CHECK.

1,218,197.

Specification of Letters Patent.

Patented Mar. 6, 1917.

Application filed April 14, 1916. Serial No. 91,200.

To all whom it may concern:

Be it known that I, EBEN H. MACKINLAY, a subject of the King of England, residing at Calgary, in the Province of Alberta, Dominion of Canada, have invented certain new and useful Improvements in Door-Checks; and I do hereby declare the following to be a full, clear, and exact description of the invention, such as will enable others skilled in the art to which it appertains to make and use the same.

This invention relates to improvements in door checks.

One object of the invention is to provide a novel and simple device of this character which is adapted to be applied at the hinge side of the door to prevent banging of the door, when the door is mounted on spring hinges.

Another object is to provide a device of this character which is simple in construction, and one that can be manufactured and installed at a comparatively low cost.

Other objects and advantages will be apparent from the following description when taken in connection with the accompanying drawing.

In the drawing:

Figure 1 is an elevation of a portion of a door and frame, the door being partially broken away to show my invention in elevation;

Fig. 2 is an enlarged horizontal sectional view on the line 2—2 of Fig. 1;

Fig. 3 is an enlarged horizontal section on the same line, but showing the door in open position, and the device ready for action when the door is to be moved into closed position;

Fig. 4 is an enlarged vertical section on the line 4—4 of Fig. 1.

Referring particularly to the accompanying drawing, 10 represents a portion of the door which is mounted on the frame 11 by means of the spring hinges 12 in the adjacent edge of the door, and at a point approximately intermediate the hinges there is formed a mortise 13 into which is inserted a tubular member 14, the bore of which has a spiral groove 15 formed throughout a portion of the length thereof and intermediate the ends. Thus, the outer portion of the bore, as well as, the inner portion is smooth. A flange 16 is formed on the outer end of the tubular member 14 and is countersunk in the edge face of the door. An opening

17 is formed in the outer end of the tube and receives therein a plug 18, the marginal portion of which projects beyond the end of the tube and is held from outward movement from the tube by a flange 19 which engages the inner face of the end of the tube. A recess 20 is formed in the inner end of the plug to receive the head 21 of a bolt 22 which extends longitudinally and centrally through the tube.

Disposed within the center of the tube is a cylindrical member 23 having a spiral rib 24 on its peripheral face, which engages in the spiral groove 15. Encircling the bolt 22, 70 and bearing with its opposite ends respectively against the inner face of the plug and the outer end of the cylindrical member 23 is a strong coil spring 25 which acts as a buffer when the plug 18 strikes a wear plate 75 26 secured to the adjacent faces of the upright stile of the door frame. In the other end of the cylindrical member is formed a recess 27 which receives the outer end of a lighter coil spring 28, said spring also encircling the bolt, and bearing with its other end against a transversely extending plate 29. This plate is formed with a pair of openings 30 through which extend the guiding pins 31 secured to the inner end of the 80 tubular casing 14. The inner end of the bolt is threaded through the said plate at 29'.

Normally, the plug 18 will project beyond the outer end of the tubular member, and the cylindrical member 23 disposed at the 90 outer end of the spiral groove 15. When the door is moved into closed position, by the force of the springs of the hinges, the plug will be forced into the tubular member so as to compress the spring 25. This pressure 95 on the spring will cause the spring to exert pressure inwardly against the member 23 thus causing said member to rotate by reason of the engagement of its rib with the groove of the tubular member. The spring 100 25, being stronger than the spring 28, will easily overcome the spring 28 so as to force the member 23 inwardly. Now, if the door be suddenly closed the spring 25 will be compressed before the block 23 has time to 105 rotate and release the tension on said spring 25, said spring thus effectually checking the door against any sudden closing. However, as the door moves farther from the first checking position into closed position the 110 block 23 will rotate and the slow movement following the checking will be taken up by

the spring 28. Again, if the door is closed slowly the spring 25 will be compressed very little or not at all, the block 23 moving in a substantially synchronous manner with the 5 plug 18 so that the checking is accomplished entirely by the light spring 28. When the door is pulled into open position, the spring 25 will exert outward pressure against the 10 plug 18 so as to cause the same to project beyond the end of the tubular member. The pressure of the spring 25 against the member 23 being thus relieved, the spring 28 can 15 expand and force the member 23 to the outermost limit of its movement. The parts are then in position to again act when the door is permitted to close under the influence of the spring hinges.

What is claimed is:

1. A door check comprising a cylinder 20 disposed within the hinged edge of a door, a buffer head projecting from the outer end of the cylinder, the intermediate portion of the interior wall of the cylinder being grooved, a spirally ribbed member disposed

within the cylinder and engaging in the 25 groove, a pin disposed centrally through the ribbed member, a head formed on one end of the pin and slideable within the buffer head, a spring disposed between the ribbed member and the buffer head, and a weaker 30 spring disposed between the ribbed member and the other end of the cylinder.

2. A door check comprising a cylinder, a buffer head projecting from the outer end 35 of the cylinder, the intermediate portion of the interior walls of the cylinder being grooved, a spirally ribbed member disposed within the cylinder and engaging in the grooves, a spring disposed between the ribbed member and the buffer head, and a weaker 40 spring disposed between the ribbed member and the other end of the cylinder.

In testimony whereof I affix my signature, in the presence of two witnesses.

EBEN H. MACKINLAY.

Witnesses:

E. M. JACOBS,

WILLIAM A. MACDONALD.
